UNITED STATES PATENT OFFICE.

NICHOLAS G. ABBATE, OF BALTIMORE, MARYLAND.

LIFE-PRESERVER AND TRUNK.

1,112,881.

Specification of Letters Patent.

Patented Oct. 6, 1914.

Application filed June 30, 1914. Serial No. 848,162.

To all whom it may concern:

Be it known that I, NICHOLAS G. ABBATE, a subject of the King of Italy, residing at Baltimore, in the State of Maryland, have 5 invented certain new and useful Improvements in Life-Preservers and Trunks, of which the following is a specification.

My invention relates to improvements in life preservers and trunks, the main object 10 of the invention being the provision of a combination trunk and life preserver which will perform the functions of either a life preserver or trunk and which may be quickly converted into use from a trunk to 15 a life preserver as circumstances require.

Another object of my invention is the provision of a life preserver and trunk which will be compact and small in size to permit its storage in a small space or stateroom, 20 which can be instantly adapted for use as a life preserver and proved thoroughly efficient, which will be of simple and inexpensive construction, easily applied for use and which generally will be thoroughly efficient and practical.

With these objects in view, my invention consists of a combined life preserver and trunk embodying novel features of construction and combination of parts, substantially 30 as shown, described and claimed.

In order that the construction in detail and the manner of using my invention may be fully understood and its many advantages be appreciated, I have shown in the 35 accompanying drawing a combined trunk and life preserver embodying my invention.

Figure 1 represents a top plan view of the invention. Fig. 2 represents a side elevation thereof. Fig. 3 represents an end view 40 with the parts in the position they assume when the trunk is converted into a life preserver, and Fig. 4 represents a central longitudinal sectional view of the invention the parts being in the position they occupy when 45 the invention is employed as a life preserver, a human figure being shown in dotted lines. Figs. 5 and 6 represent a view in section and end elevation of a preferred form of cover for the trunk.

50 Referring by numeral to the drawings in which similar characters are used to designate corresponding parts in all the views of the drawings. The numeral 1 designates the main portion or receptacle of the trunk, 55 provided in its bottom wall with an opening 2, normally covered by a hinged door 3,

having latch 4' and to the trunk is secured by suitable fastenings 4, the top or cover 5, which has a lock 6, and is provided with an opening 7, to receive a protecting cap or cover 8, or to receive a ventilator 9, whose purpose is to supply air when the improvement is used as a life preserver. Secured within the trunk and fitting snugly against its walls is the canvas or like bag 10, whose upper end is open and whose lower portion is reduced to provide the pair of leg receiving members 11, the bag normally having its upper portion collapsed and fitting in the upper space 12 of the trunk, while the 60 leg portions normally fit and are received in the space 13, in the bottom of the trunk, thus neatly and compactly receiving and storing the bag when not in use, said bag being further provided with cases or pockets 65 14, to receive suitable food.

The lower portion of the trunk is provided with a lining 15, of cork or buoyant material, which extends entirely around the trunk and is provided with leg receiving 70 openings 16, which align with the openings in the upper portion of the leg receiving members 11, and at one end a case 17, is provided adapted to receive vessels 18, containing liquid refreshment, said case being 75 provided with a cover 19. From this construction it will be observed that the trunk has mounted therein the bag which can have its upper portion extended or raised to form a canopy or protector, which is secured in 80 open position by the rectangular frame 20, secured by fastenings 21, to the bag and by fastenings 22, to the lid or cover and sustained in raised position by means of the two sets of braces 23, hinged or pivoted 85 at their lower ends 24, to the upper portion of the trunk and having their upper ends adapted to be secured by fastenings 25, to the top of the trunk. The leg members depending from the bottom of the 90 trunk and receiving the legs 26, of the person, while the body portion 26', of the person extends into the trunk and canopy and is properly supported by the band 27, which 95 passes around the body and over the shoulders.

100 It will be observed that the person can stand within the apparatus, or may occupy a sitting position and the bag in one end is provided with the circular window 28, 110 and the elongated window 28', which windows when the person occupies the apparatus

will come in proper line of the vision of the person.

From the foregoing description taken in connection with the drawings the manner of using my invention will be readily understood and it will be apparent that when used as a trunk the top fits the main portion as usual with the bag and leg members stored within said main portion, the space within 10 said main portion being ample to receive the apparel and other articles necessary for the traveler and that the trunk is of a size to enable its storage in the stateroom or other place without inconvenience to the traveler. In the event that it is found necessary to use the trunk as a life preserver the bag is extended or raised and the frame, hinged braces and top are adjusted to form 15 a canopy and the leg members are projected 20 through the bottom of the trunk enabling the person to adjust the entire apparatus to their person and in this manner to be cast or jump into the water, the apparatus thus floating with the person safely incased in 25 the apparatus.

The invention serves the double purpose of a trunk and life preserver and can be quickly converted from a trunk to a life preserver and in stormy weather the entire 30 canopy may be closed and the ventilator applied to the top, or the top may be removed and the bag remain in extended and opened position to enable the occupant to be amply supplied with air and to enable 35 them to navigate the apparatus with a degree of certainty.

The invention is capable of production at a low price, can be made in any size desired and will perform its functions in an 40 efficient and practical manner.

In the construction shown in Figs. 5 and 6, I provide a preferred and desirable form of cover, consisting of the inclosing frame 30 adapted to fit upon the trunk or main 45 portion 1 and be secured normally by fastenings 31, and having hinged thereto at 32, the two-part cover 33, adapted to be secured by the lock 34, and one member or

section of which carries the ventilator 35. The cover is connected to the bag in any 50 desired manner and can be easily used in performing its functions as a trunk cover or when the device is used as a life preserver.

I claim:

1. A life preserver and trunk, consisting 55 of the main portion, the cover for said portion, and a bag fitting and received in said main portion and adapted to provide an upper canopy portion and lower leg receiving portions.

2. A life preserver and trunk, consisting of the main portion having openings in its bottom wall, a bag forming the lining for 60 said main portion and consisting of lower leg receiving members, and an upper canopy portion, and means for securing the canopy portion in raised position.

3. A life preserver and trunk, consisting of the main portion and cover, a bag forming the lining for said main portion and 70 comprising lower leg receiving members and an upper canopy portion, a supporting frame for retaining the canopy portion in extended position, and a cover connected with said upper portion.

4. A life preserver and trunk, consisting of the main portion and cover, a bag fitting the main portion and comprising lower leg members and an upper canopy portion, a 75 frame for supporting the canopy, a ventilator mounted in the cover, and sight windows mounted in said canopy portion.

5. A life preserver and trunk, consisting of a main portion having an opening in its bottom wall, a cover for said opening, a 80 cover for the main portion having an opening therein, a bag mounted in the main portion and providing a canopy and leg members, and a supporting frame for said canopy.

In testimony whereof I affix my signature in presence of two witnesses.

NICHOLAS G. ABBATE.
